UNITED STATES PATENT OFFICE.

JOSEPH STUBBERS, OF COVINGTON, KENTUCKY, ASSIGNOR TO THE INCANDESCENT LIGHT & STOVE COMPANY, OF CINCINNATI, OHIO.

SAFETY APPLIANCE FOR GASOLENE-TANKS.

SPECIFICATION forming part of Letters Patent No. 766,778, dated August 2, 1904.

Application filed February 27, 1903. Serial No. 145,392. (No model.)

To all whom it may concern:

Be it known that I, JOSEPH STUBBERS, a citizen of the United States, and a resident of the city of Covington, in the county of Kenton and State of Kentucky, have invented a certain new and useful Improved Safety Appliance for Gasolene-Tanks Subjected to Pressure from Within Outward, of which the following is a specification.

10 My invention relates to gasolene-tanks which are subjected to a pressure exerted within and pressing outward against the walls of the tank. Such tanks may be subjected to such pressure by having gas or vapor pumped into them by 15 a force-pump or by carrying gasolene subjected to heat, which latter generates vapor. The rapidity with which vapor is generated depends upon the amount of heat communicated. With reference to the generation of vapor in 20 the tank by heat, it should be noted that this generation may occur in the regular operation of a gasolene-generator connected to the tank or may occur by an accident, whereby the tank 25 is subjected to an unexpected outward contact with heat, especially in the condition of flame.

One feature of my invention consists in providing safety appliances substantially as hereinafter specified, which prevent in the tank any pressure to a degree beyond that which is 30 safe.

Another feature of my invention consists in a means for automatically reducing any pressure in the tank before the tank is opened and for so reducing the pressure that the vapor 35 of gasolene under pressure shall be conveyed away to a place where its fumes shall do no harm.

The several features of my invention and the various advantages resulting from their 40 use, conjointly or otherwise, will be apparent from the following description and claims.

In the accompanying drawings, making a part of this application, and in which similar letters of reference indicate corresponding 45 parts, Figure 1 represents a side elevation of a gasolene-gas generator and gasolene-tank combined therewith and a construction applied thereto illustrating my invention. Fig. 2 represents in vertical central section that

portion of the mechanism shown in Fig. 1, 50 which more particularly illustrates my invention. This figure shows the mechanism on a larger scale than it is shown in Fig. 1. Fig. 3 represents an elevation of the fill-plug, and Fig. 4 is a vertical central section of the fill-sleeve. Fig. 5 is a section, vertical and central, of the rupturable disk and the chamber which contains it, illustrating another mode of uniting the separate parts of the chamber. Both Figs. 3 and 5 are on the same scale as 55 Fig. 2.

I will now proceed to describe my invention in detail.

A indicates a gasolene-tank, which preferably is made of seamless copper and without 60 soft-soldered joints. One of the preferred modes of making the tanks consists in forming a shell out of one piece by what is known as the process of "drawing" it up and onto this shell securing a brass head, preferably 65 by brazing or casting it thereto.

The tank is to be suitably upheld. In the present illustrative instance the tank is duly supported on standards A², supporting bands A³, extending under and above the tank and 70 connected at A⁴. The brass head on this tank may have the lugs A⁵ and A⁶, which are drilled and tapped for the purpose of respectively connecting the generator and initial-heat burner; but the connection of these to the 75 tank may be made in any secure manner.

The generator may be of any suitable design, the one shown here being selected on account of its simplicity.

T indicates a gas (or vapor) delivery valve. 80

N indicates the initial-heat burner.

P is a cylinder located over the generator for the purpose of preventing the products of combustion coming from the subflame-burner from entering into the commingling-tube and 85 also for the purpose of preheating the air before it is mixed with the vapor.

The cylinder is open at a proper place or places to receive the fresh air to be mixed with the vapor of gasolene delivered from 90 the valve T. To facilitate this cylinder for receiving such fresh air, I make it open at one or both ends. These openings in the cyl-

inder for the reception of fresh air may be protected with a wire screen to prevent any flame from entering into the mixing-tube.

R indicates the subflame-burner. A pipe 5 R² connects the delivery-pipe P² to the subflame-burner for the purpose of supplying the subflame-burner with some of the mixed vapor and air, which mixture passes up into this delivery-pipe P² and is thereby conveyed to the 10 burners or other desired point. This mixture of vapor and air is composed of vapor ejected from the valve T into the cylinder and into the delivery-pipe and on its way thither mixed with the air entrained from outside into the 15 cylinder P through the aforementioned air-inlet openings of it.

S indicates the generator for generating the gasolene vapor.

W indicates a shield to prevent the sub- 10 flame of the subflame-burner R from being blown out.

N³ indicates a conduit for conducting the vapor to the initial - heat burner N. Of this burner N⁴ indicates the delivery end of the 15 valve and N² the hand - wheel or equivalent means for regulating this valve N⁴.

V indicates a conduit for conducting gasolene from the tank A to the generator S.

In view of the state of the art further description of the construction of this apparatus for generating vapor of gasolene and intermingling that vapor with air is deemed unnecessary.

Suitable means for creating a pressure in 5 the tank A and continuing such pressure therein are to be employed. In the present exemplification I have shown one kind of such means—to wit, an air-pump B, provided with a preferred kind of suitable base B⁴. A pipe 100 C is the connecting-conduit from the pump to the gasolene-tank A.

B³ indicates the piston-rod of the pump, and B² a handle for operating such rod. A strap B⁵, connecting the barrel of this pump to the 105 tank, serves as a convenient means of upholding it and of making it portable with the tank A.

At the place where the tank A is to be filled with gasolene I locate a device described as follows: A sleeve or receptacle D is provided and an interior or female screw-thread D² and lower down with a shoulder D³. Below this shoulder the interior of the sleeve is duly connected to the interior of the tank A by the 110 extension or conduit D⁴. The interior of this sleeve is connected to the interior of a pipe E² by a conduit E. D⁵ indicates the fill-plug, provided exteriorly with a screw-thread D⁶, which latter engages the screw D² of the sleeve 115 D. The upper end of this plug is formed so as to be capable of being duly rotated. A simple mode of forming it for this purpose is by making a slot D⁷ in it to accommodate a wrench or any suitable instrument for screwing the plug down in the sleeve or up and out

of the latter. D⁸ is a screw which passes through the plug centrally or substantially so. The head of the screw is at the upper side of the plug and cannot pass through the plug. The other or free end of this screw D⁸ 70 passes down below the plug and is screwed into the metal disk D⁹. This disk D⁹ has a downwardly-extending screw-threaded projection D¹⁰, around which at its upper part is a gasket D¹¹, held in place by a nut D¹², screwed 75 onto this projection D¹⁰. This metal disk D⁹ has also a cone-shaped projection D¹⁴ centrally disposed on its upper side, and the bottom part of the plug D⁵ is countersunk, so that the disk D⁹ will touch the plug D⁵ only at the 80 raised or upper part of the projection D¹⁴. Such a construction allows the disk D⁹ to swing, so that when it (its gasket) touches the shoulder D³ of the sleeve D it can and will settle down level and will not turn when plug 85 D⁵ is screwed up tighter, but will merely be pressed down onto this seat (annular shoulder) D³, thereby preserving the gasket and making a tighter joint. The disk D⁹ is smaller in diameter than the inside diameter of sleeve D, 90 so as to allow the vapor to pass freely around the disk when the same is removed from the shoulder D³ and pass through orifice D¹⁵ into pipe E. Although this mode of constructing the sleeve, plug, and gasket and this provision 95 of this device for keeping the gasket level, &c., are of my invention and constitute the preferred construction, yet the construction may be altered without affecting those principal features of my invention hereinafter described. Thus, for instance, the common mode of putting the gasket below the plug might be used or other modes be employed without materially affecting the principal features of invention.

The sleeve D has an opening D¹⁵ in one side, with which one end of the pipe E aforementioned communicates. This opening is preferably close to the shoulder D³, where the plug makes its joint.

One end of the pipe E² leads to the outside of the building or to some place where the gas or vapor escaping therefrom cannot cause an accident. The other end E³ of this pipe is connected with a chamber H. The chamber 115 is preferably made in two separable parts—viz., H² and H⁶—for enabling the interior of the chamber to be reached. These parts are preferably connected by means of lugs H⁴ on part H² and lugs H⁵ on part H⁶ and bolts H³. The latter hold adjacent lugs H⁴ and H⁵ together in the well-known manner. A suitable conduit or passage-way H⁷ connects the chamber H to the gasolene-tank A.

The chamber H contains a diaphragm K, 125 which consists of light sheet metal. In Figs. 1 and 2 this diaphragm K is shown raised somewhat in the center. This is the position it assumes when there is a pressure in the tank. A device for rupturing this diaphragm when 130

this pressure exceeds that which is safe or desired, as hereinafter more particularly specified, is present. This rupturing-abutment consists of a pin M, whose lower end is adapted to stand in the way of the diaphragm and meet it as it is raised by the pressure of the gas and vapor of the tank and when the pressure exceeds the amount fixed upon and the diaphragm continues to rise shall duly rupture it.

It is desirable to be able to regulate or adjust the device so that the disk K may burst at any desired pressure. Several desirable modes of effecting this regulation are, first, by providing means for lowering and elevating the pin M; secondly, by making the lower end of the pin more or less pointed; thirdly, different thicknesses of metal for the diaphragm may be employed. The first method of providing means for elevating and lowering the pin M may be conveniently carried out by providing the pin M with a screw-thread M², engaging a female thread in the boss H² of the chamber. Rotation of the pin in the proper direction operates to elevate or lower the pin, as desired, thereby bringing it nearer to or farther away from the diaphragm K. If desired to have the sheet-metal diaphragm ruptured at less pressure, then the pin M should be screwed down. If desired to rupture the diaphragm at a greater pressure, then the pin should be screwed up.

The end of the pin M which is next to the diaphragm is preferably provided with a button M², and this button M², when present being the end of the pin, may be more or less pointed, as and for the purpose aforementioned.

It is an object not to have the button press against the metal disk K when there is little or no pressure in the tank. The disk K may be soldered to the bottom or lower portion of the chamber H or be otherwise fastened to it in any suitable manner. The attachment when the arrangement is as shown will be at or near the peripheral edge.

The object of having the chamber H in separable divisions is primarily so that in case the disk be ruptured ready access to the interior of the chamber can be had to remove the ruptured disk and to replace it with a new one.

The separable divisions of the chamber may obviously be connected in various ways. For instance, part H² may be smaller in diameter than part H⁶ and have a male thread and part H⁶ have a female thread, and in this event part H² may serve to clamp disk K in place and make a perfect joint. (See Fig. 5.)

Having now described the principal features of this invention, I will proceed to describe the operation. The generator is heated in the well-known manner by pumping air into the tank A containing the gasoline and opening and lighting the initial-heat burner N. The air is carbureted by the air coming

in contact with the gasoline in the tank. While heating the generator air under pressure has to be introduced into the tank. In the present illustrative instance it is pumped into the tank. After the generator is heated sufficiently to generate vapor in the generator S then the valve T is turned on and the vapor shoots therefrom, passing into mixing-tube Q. The spouting of the vapor entrains the air into the commingling-tube Q and mixes with the same and is carried through pipe P² wherever desired. Some of this vapor, however, after it enters pipe P² passes through pipe R² into the subflame-burner R and is there ignited, which thereafter keeps the generator hot, after which the initial-heat burner should be turned off. The gasoline is fed from the tank A into the generator S through pipe V. The pressure in the tank may be maintained by re-pumping air into the tank or in some other mode. When it is desired to refill the tank, plug D² must be removed. When the plug is unscrewed only half a turn, the gases under pressure in the tank will immediately pass through the pipe E into pipe E² and from there to the outside of the building or some other place where the fumes will do no harm. Another feature is that before the plug D² is unscrewed all the way all the pressure would be out of the tank, and on account of the pressure being exhausted the subflame at generator will be automatically extinguished, for the reason that without the pressure there is no vapor forced out of the needle-opening.

It is a well-known fact that gasoline when heated expands very rapidly, and it has occurred with many gasoline devices that under such circumstances the tank bursted and disastrous results would follow, and with certain other gasoline devices which have soldered joints the solder would melt and then the gas would escape into the room, increasing the fire. In many instances the flame burning around the tank was at first very small; but when the solder melted in the joints the gas would suddenly escape, making a large fire. It is therefore desirable that in the first place the tank should not have any soldered joints and in the second place that the tank cannot burst under any condition and in the third place that the gas cannot escape into the room under any condition. In my invention when too much pressure is created the disk K will bulge upward, as shown in drawings. It will be pressed up against the button M² on pin M, and soon thereafter it will rupture. When the disk K ruptures, the vapor in the tank A will escape through the connecting-pipe H' and from there pass through the ruptured disk K, thence through the pipe E² to the outside of the building. It will be noted that the pipe E² is used for two purposes. One is to carry the vapor under pressure out of the tank when the machine is to be filled and prior to this filling

and the other is for carrying the vapor out of the tank when the disk K ruptures. It will also be seen that instead of using a disk that will rupture I could use a safety-valve; but as it is absolutely necessary that the safety-valve should be perfectly tight, which may be difficult to obtain, I prefer a disk that will rupture at the proper time. At other times the disk has perfectly tight joints.

What I claim as new and of my invention, and desire to secure by Letters Patent, is—

1. The combination of a gasolene-tank, a sleeve connected thereto, a pipe connected to the sleeve and leading to a proper place for the discharge of vapor, or gas, a fill-plug adapted to engage said sleeve, the fill-plug and the sleeve being mutually constructed for enabling the vapor under pressure in the tank to escape through this pipe, before the fill-plug is removed, substantially as and for the purposes specified.

2. In combination with a gasolene-tank, means for maintaining pressure therein, an enclosed safety device adapted to escape gas under the predetermined pressure, and an es-

cape-pipe leading from said safety device, a filling device having a by-pass and a pipe connecting said by-pass to said safety escape-pipe and a filler-plug for closing the tank below the by-pass, said plug likewise closing the by-pass when the same is in position to close the filling-opening into said tank, substantially as described.

3. In combination with a gasolene-tank, means for maintaining pressure therein, an enclosed safety device adapted to escape gas under a predetermined pressure, a filling device, means for escaping the accumulated gas from the tank when the filling device is opened, and an externally-conducted escape-pipe having branch connections with both of said devices for escaping gas from the tank, substantially as described.

In witness whereof I have set my hand to this specification in the presence of two subscribing witnesses.

JOSEPH STUBBERS.
